UNITED STATES PATENT OFFICE

CHARLES N. CORYELL, OF MAMARONECK, NEW YORK

VANITY CASE

Application filed November 26, 1928. Serial No. 321,797.

The invention relates in general to containers, and more particularly to vanity cases for holding cosmetics and the like.

According to one form of the invention the vanity case comprises a pair of hinged covers with a mirror section therebetween. The vanity case may be of general rectangular configuration with straight side walls, certain of which may be continuous from top to bottom thereby providing uninterrupted surfaces. The mirror section may have a spring catch secured thereto for holding both covers closed in such manner that, upon operating the catch, either cover may be opened exposing, at the will of the user, either rouge or powder. The cosmetics may be in the form of compacts which may be held in the covers by a special spring lug construction operated by a common pin, greatly facilitating removal of the compacts whenever it is desired to insert a refill, and providing an attractive appearance. Furthermore, one or both of the covers may have at its exterior surface a design member of open construction, the cover and design being of different appearance or color to produce contrasting effects.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a perspective of the box closed;

Fig. 2 is a perspective of the box opened exposing one side for use;

Fig. 3 is a section through the box with one cover open;

Fig. 4 is a plan view of the box open with the mirror in raised position;

Fig. 5 is a perspective of the bezel;

Fig. 6 is a detail of the spring lug; Fig. 7

is a perspective of the catch secured to the mirror; and

Fig. 8 is a detail showing the manner of mounting the design member.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinafter defined and claimed.

Referring now to the drawing, the vanity case comprises a base cover 1, a top cover 2 and a metal mirror 3 all hinged together by the same hinge, each part having hinged knuckles secured thereto and a common pin 4 passing through all the knuckles. As shown in Fig. 1, the box is straight sided, of general rectangular configuration having beveled corners and beveled edges.

The base cover 1 comprises a bottom wall 5, a front wall 6, back wall 9 and side walls 7, the side walls extending substantially the entire height of the box. The corners of the cover are beveled forming small bevel walls 8. The edges of the cover are also beveled as indicated at 18.

Disposed within the cover is a bezel member 10, comprising a flat plate 19 fitting the side walls of the box and having a shallow recess 11 at its front edge. The bezel member 90 has a depending cylindrical wall 12 which has a lug 13 pressed out and a hole 14 diametrically opposite the lug. A band 15 of spring material is riveted to the cylindrical wall, this band having a V-shaped lug 16 disposed in the hole 14. Over the band, near the lug 16, the plate is provided with an opening 17, so positioned that, when a common pin (not shown) is inserted therein, the pin wedges itself between the band 15 and wall 100

12. As the pin is pushed into the hole 17, the band 15 is forced away from the wall 12 against the elasticity of the band to remove the lug 16 from the space bounded by the cylindrical wall. 5

13. A compact 20 which may be of the flat type comprising a backing 21 having a flat base and conical wall 22, filled with compacted cosmetic material 23, such as powder, is 10 positioned within the cylindrical wall 12 and held beneath the fixed lug 13 and spring pressed lug 16.

14. The top cover 2 is of a construction similar to the base cover 1, having a front wall 28, 15 a back wall 29, side walls 30, bevel walls 31 and bevel edges 32. The front and back walls and bevel walls align with the corresponding walls of the base cover when the case is closed, but the side walls 30 slide with 20 in the side walls 7 on the base cover, the side walls 7 extending up to the beveled edges 32 of the top cover as shown.

15. The top cover 2 has a bezel member 34 with a pin operated spring lug, a compact 35 filled 25 with cosmetic material which may be rouge, all being of a similar construction to similar elements in the base cover. However, if desired, the opening in the bezel 34 and the compact 35 may be smaller than similar parts 30 in the base cover.

16. The mirror section comprises a mirror 3 of sheet metal polished on both sides to provide mirror surfaces and having an integral hinge knuckle through which the common 35 pintle 4 passes. This section has a shallow recess 36 in its edge. A catch member 37 which comprises an elastic strip 38 having ears 39 at the ends thereof is provided, these ears being disposed on opposite sides of the 40 mirror and riveted by rivets 40 or otherwise secured to the mirror section. The spring strip 38 has upper and lower catch lugs 41 and 42 for engaging recesses 43 and 44 formed respectively in the top and base covers. A 45 flat finger piece 45 has a reduced portion passing through the spring strip 38 and riveted thereover. This finger piece seats in the recess 46 and 47, half in each cover when the case is closed.

50. One or both covers may be provided with special ornamental design plate 48 of open network construction illustrated in Fig. 1 by the letter R, which has rivet portions 49 secured thereto passing through the bottom 55 wall of the cover and riveted thereover, as illustrated in Fig. 8. The cover may have a finish of one appearance, while the design plate may have a finish of another appearance which may contrast sharply with the 60 appearance of the cover, producing a striking and pleasing effect. For instance, the cover and design may be of different metals, or different colored enamels may be applied to these members.

65. It will be seen that the mirror divides the

box into two compartments, each entirely separate from the other and that sufficient space is provided in each compartment for a powder puff. The construction is such that either cover may be removed from the mirror 70 at will, providing access to the compartment desired without interfering with the other compartment. The box is of striking appearance because of the smooth sides presented by the side walls extending substantially the 75 entire height of the box. The appearance is also improved by the design of contrasting colors as described above. Furthermore, the compacts may be removed very simply and the holding devices are hidden from view and 80 take up but little space. In short, a very neat and compact vanity box is provided holding considerable material and yet presenting a neat and graceful appearance.

85. While certain novel features of the invention have been shown and described and are pointed out in the annexed claims, it will be understood that various omissions, substitutions and changes in the forms and details of the device illustrated and in its operation 90 may be made by those skilled in the art without departing from the spirit of the invention.

95. What is claimed is:

1. A vanity box comprising a cover, a sheet metal mirror, means hingedly connecting said mirror and cover, said mirror having a shallow recess in its edge opposite said hinge means, a catch member comprising a spring strip spanning said recess and secured 100 to said mirror on opposite sides of said recess, a push member attached to said spring strip and a catch attached to said spring strip for engagement with said cover.

105. 2. A vanity box comprising a cover, a flat section, means hingedly connecting said section and cover, said section having a shallow recess in its edge opposite said hinge means, a catch member comprising a spring band spanning said recess and secured to said section on opposite sides of said recess, a push member attached to said spring strip and a catch attached to said spring strip for engagement with said cover.

110. 3. A vanity box comprising a cover, a bezel member in said cover and comprising a flat plate with an inner depending cylindrical wall forming a recess, said wall having an abutment and an opening, a flat spring band secured at one end to the outside of said wall, 115 a lug on the free end of said band positioned in said hole, a toilet article in said recess and held under said abutment and lug, said plate having a pin hole over said band so that a pin inserted in said pin hole enters 120 between said band and wall to move the lug away from said article and recess.

125. 4. A vanity box comprising a cover, having a plate with a wall extending therefrom and forming a recess, said wall having an open- 130

ing, a spring member behind said wall, a lug operated by said spring member and positioned in said opening, a toilet article in said recess and held under said lug, said plate having a pin hole near said lug so that a pin or the like must be inserted in said pin hole to force the lug away from said article and recess.

5. In a vanity box, base and top covers each comprising a bottom and upstanding front, back and side walls, the side walls on the base cover disposed outside of the corresponding walls on the top cover and extending substantially to the bottom of the top cover, a mirror between said covers and dividing the box into two compartments, hinge means connecting the covers and mirror and a spring catch secured to said mirror and having catch lugs on opposite sides for engagement with 20 said covers to hold the box closed.

6. In a vanity box, substantially rectangular base and top covers each comprising a bottom and upstanding front, back and side walls, the side walls on the base cover being disposed outside of the corresponding walls on the top cover and extending substantially to the bottom of the top cover, a metal mirror between said covers and dividing the box into two compartments, a common hinge connecting the covers at the back walls thereof and the mirror, the front walls of the covers having recesses, a spring catch secured to said mirror and having catch lugs on opposite sides for engagement with said recesses, the front and back walls on the base cover being of substantially the same height as corresponding walls on the top cover, said front and back walls on the base cover being in substantial alignment with corresponding walls on the top cover when the box is closed.

7. A vanity box comprising a pair of comparatively shallow covers, means separably connecting said covers, toilet articles in said covers, each cover comprising a bottom wall and upstanding side walls, at least one of the side walls of the first cover extending substantially to the bottom wall of the other cover when the box is closed to present an unbroken side wall when the box is closed, 50 at least one of the remaining side walls of the first cover falling short of the bottom wall of the other cover when the box is closed to permit easy access to said toilet articles when the box is open.

8. A vanity box comprising a pair of comparatively shallow covers, means separably connecting said covers, toilet articles in said covers, each cover comprising a bottom wall and polygonal upstanding side walls, oppositely disposed side walls of the first cover overlapping the corresponding side walls of the other cover and extending to the bottom wall of the other cover when the box is closed to present unbroken side walls when the box is closed, the remaining walls of said first

cover meeting the corresponding walls of the other cover in substantially edge-to-edge abutting relation when the box is closed to permit easy access to said toilet articles when the box is open.

9. A vanity box comprising a metal double faced mirror, a single push catch carried directly by said mirror, top and bottom covers hingedly connected to said metal mirror and held in closed position by said push catch, whereby either cover may be opened after operation of said push catch, said push catch comprising a single finger-engaging portion and two catch portions for engaging said covers respectively.

10. A vanity box comprising a metal double faced mirror having a recess in one edge, a single push catch disposed in said recess and carried directly by said mirror, top and bottom covers hingedly connected to said metal mirror and held in closed position by said push catch, whereby either cover may be opened after operation of said push catch, and different cosmetics carried in said covers, said push catch comprising a single finger-engaging portion and two catch portions for engaging said covers respectively.

11. In a vanity box, base and top covers each comprising a bottom and upstanding front, back and side walls, the side walls on the base cover disposed outside of the corresponding walls on the top cover and extending substantially to the bottom of the top cover, the front and back walls of each cover meeting substantially midway between the bottom walls of said covers when the box is closed, and hinge means connecting said covers at said back walls.

In testimony whereof I have hereunto set my hand.

CHARLES N. CORYELL.
